A. I. RISER,
NON-FOAMING MEASURING CUP,
APPLICATION FILED OCT. 6, 1920.

1,385,495.

Patented July 26, 1921.

INVENTOR:
Arthur I. Risser
By Gleeson & Cox Atty.

UNITED STATES PATENT OFFICE.

ARTHUR I. RISSE, OF CHICAGO, ILLINOIS, ASSIGNOR TO U. S. BOTTLES MACHINERY CO., OF CHICAGO, ILLINOIS, A CORPORATION OF ILLINOIS.

NON-FOAMING MEASURING-CUP.

1,385,495.

Specification of Letters Patent. Patented July 26, 1921.

Application filed October 6, 1920. Serial No. 415,008.

To all whom it may concern:

Be it known that I, ARTHUR I. RISSE, a citizen of the United States, residing at Chicago, in the county of Cook and State of Illinois, have invented a certain new and useful Improvement in Non-Foaming Measuring-Cups, of which the following is a specification.

This invention relates to machines for automatically filling bottles with a definite predetermined measured quantity of liquid. One such machine is shown in my prior United States Patent 1,360,023, dated November 23, 1920.

The object of the invention is to provide means for filling a measuring cup intended to deliver liquid to a bottle without allowing the liquid to foam in the cup, thereby preventing inaccuracy on the part of the cup in delivering the predetermined amount of real liquid material into the bottle.

The invention consists in means for carrying out the foregoing objects which can be easily and cheaply made, which is satisfactory in use and not readily liable to get out of order. More particularly the invention consists in means so directing the liquid that it passes upward all around the cup and thence over the upper edge in a thin stream from which practically all foam is removed. More particularly, the invention consists in means and features of details hereafter more fully set forth in the specification and claims.

Referring to the drawings in which similar numerals represent the same parts throughout the several views,

Figure 1 is a sectional view of a cup filling mechanism of a machine of the type of said prior application, having the mechanism of this invention applied thereto.

Fig. 2 is a changed position view of the central portion of Fig. 1.

Fig. 3 is a perspective view of the central parts shown in Fig. 2.

Fig. 4 is a plan view on the line 4-4 of Fig. 3.

As fully set forth in said prior patent application, 10 is a stationary plate from which a liquid displacing block 12 is suspended by rods 14 and from which is also slidably suspended a valve rod 16.

Inclosing the parts just described and vertically reciprocatable with reference thereto by means fully shown in said prior applica-

tion is a liquid supply tank 18, perforated to receive the stem 19 of a measuring cup 20, screw threaded to place at 22 and locked by a nut 23. The lower end of this cup device terminates in a nozzle 24 having a central 60 perforation 26 generally closed by valve rod 16, as set forth in said prior application. The law of the machine is such that with the parts in the position of Fig. 1 the liquid 28 in tank 18 is raised, by the presence of block 65 12, to a sufficient height so that it flows over the upper edge 28 of the cup and fills it and that with the parts in the position of Fig. 3 this flow ceases, leaving the cup full until valve 16-26 opens and lets the liquid flow 70 into the bottle, leaving the parts appearing as in Fig. 2.

The problem to be solved is to prevent the liquid 28 from foaming in cup 20 as it rushes from the position of Fig. 2 to that 75 of Fig. 3 over the cup edge 28. The result is accomplished by surrounding the cup 20 with a larger stationary tubular member 32, extending to the top of tank 18, said tube being of sufficiently large interior diameter so that, in combination with vertically placed ribs 34 on the sides of the cup, parallel vertical passages 36 are formed leading from ports 38 formed in the base of tube 32 up to the upper edge of the cup. 85

The result of this construction is that as the tank 18 and attached parts move from the position of Fig. 2 to that of Fig. 1 the liquid in the tank outside the tube 32 passes through the ports 38 and up the passages 90 36 in comparatively thin wide streams from which the foam producing gas readily escapes as the liquid reaches and passes over the edge 28 of the cup with the result that the liquid in cup 20 proper is solid, placid 95 and without foam, whereby an accurately measured amount of liquid passes down through nozzle 26 into the bottle when, after the cup 32 is filled, the valve 16 opens passage 26, as fully set forth in said prior application. 100

Having thus described my invention what I claim as new and desire to secure by Letters Patent is:—

1. In mechanism of the class described, 105 an open mouthed cup and stationary means around the cup providing passages from points below the edge of the cup upward to the edge of the cup, for the purposes set forth.

2. In mechanism of the class described, an open mouthed cup and stationary means around the cup providing a passage, narrow with reference to the cup diameter leading 5 from points below the edge of the cup upward to the edge of the cup, for the purposes set forth.
3. In mechanism of the class described, an open mouthed cup and stationary means 10 around the cup providing a plurality of separated passages from points below the edge of the cup upward to the edge of the cup, opening at the cup edge in slots of substantial width along the cup edge, for the 15 purposes set forth.
4. In mechanism of the class described, an open mouthed cup and stationary means around the cup providing a plurality of separated passages, narrow, with reference 20 to the cup diameter, from points below the edge of the cup upward to the edge of the cup, opening at the cup edge in slots of substantial width along the cup edge, for the 25 purposes set forth.
5. In mechanism of the class described, a cup open at its top vertical ribs spaced one from the other on the outside of the cup, and a tube inclosing the ribs to make the 30 spaces between them passages for liquid, there being in the lower portion of the tube perforations one for each such passages, for the purposes set forth.
6. In mechanism of the class described, a tank, a cup, in the tank, open at its top and 35 provided with a discharge port, stationary means around the cup forming a passage carrying liquid from a point in the tank

below the cup edge upward to the cup edge, and means for selectively causing liquid to so flow.

7. In mechanism of the class described, a tank, a cup in the tank, open at its top and provided with a discharge port, stationary means around the cup forming a passage carrying liquid from a point in the tank 40 below the cup edge and upward to the cup edge, reciprocatable means for selectively causing liquid to so flow.

8. In mechanism of the class described, a tank, a cup in the tank, open at its top and 45 provided with a discharge port, stationary means around the cup forming passages carrying liquid from points in the tank below the cup edge upward to the cup edge in a plurality of separated streams disposed 50 along the cup edge, and means for selectively causing liquid to so flow.

9. In mechanism of the class described, a tank, a cup in the tank, open at its top and 55 provided with a discharge port, stationary means around the cup forming passages narrow with reference to the diameter of the cup and broad along its circumference, carrying liquid from points in the tank below the cup edge upward to the cup edge, 60 in a plurality of separated streams disposed along the cup edge, and means for selectively causing liquid to so flow.

In witness whereof I have hereunto subscribed my name in the presence of a wit- 65 ness.

ARTHUR I. RISER.

Witness:

ANNA ROSENTHAL.
